UNITED STATES PATENT OFFICE.

PATRICK F. MALARKEY, OF MOUNT CARMEL, PENNSYLVANIA, ASSIGNOR OF ONE-HALF TO ELMER E. STRAUB, OF MOUNT CARMEL, PENNSYLVANIA.

FEED-CHUTE.

1,191,524.

Specification of Letters Patent. Patented July 18, 1916.

Application filed July 6, 1915. Serial No. 38,379.

To all whom it may concern:

Be it known that I, PATRICK F. MALARKEY, a citizen of the United States, residing at Mount Carmel, in the county of 5 Northumberland and State of Pennsylvania, have invented a new and useful Feed-Chute, of which the following is a specification.

This invention relates to feed chutes especially designed for use in connection with 10 coal separators.

As is well known to those well acquainted with the art of separating coal, it is the practice to use separators through which the coal passes in separate superposed 15 streams. Heretofore, in order to feed the coal to the separator it has been necessary to so position the feed chute that the coal after leaving the discharge end of the chute will fall onto the different shelves or tiers 20 of the separator. This has resulted in considerable breakage of the coal and consequent deterioration in value.

One of the objects of the present invention is to provide a feed chute having means 25 whereby the body of coal gravitating therewith will be divided into a plurality of streams superposed relative to each other so as thus to flow directly onto the superposed shelves or tiers of the separator without requiring any drop which might shatter the 30 coal in its progress.

With the foregoing and other objects in view which will appear as the description proceeds, the invention resides in the combination and arrangement of parts and in the details of construction hereinafter described and claimed, it being understood that changes in the precise embodiment of the invention herein disclosed, can be made within 40 the scope of what is claimed, without departing from the spirit of the invention.

In the accompanying drawings the preferred form of the invention has been shown.

In said drawings:—Figure 1 is a plan 45 view of a portion of a chute embodying the present improvements. Fig. 2 is an end elevation thereof. Fig. 3 is a section on line A—B Fig. 1.

Referring to the figures by characters of 50 reference 1 designates the main portion of the chute, the same having the usual upstanding sides 2. The lower end of the main chute is provided with a series of tongues 3 extending partly thereacross. In the present 55 instance three of these tongues have been

shown inasmuch as the body of coal gravitating along the chute 1 is adapted to be divided into three parts, but it is to be understood that where the body of coal is to be divided into fewer parts or into a greater 60 number of parts, the number of tongues 3 will be reduced or increased accordingly. The tongues 3 may be made by cutting incisions longitudinally in the bottom of the main trough 1, the inner ends of the tongues 65 being disposed along a line extending diagonally across the trough, while the outer ends of the tongues are rounded as shown at 4. The tongues are bent at angles to the inclined chute 1 so as to lie in stepped relation. 70

The uppermost tongue 3 which is located at one side of the discharge end of the chute 1 is secured to and forms a part of the bottom of one of the series of discharge chutes 75 5, this discharge chute being extended laterally from the main chute and having upstanding side walls 6 and 7. One of these walls follows the curvature of the lower end of tongue 3 and terminates in line with that side of the tongue 3 remote from the adjacent side wall 2 of the chute 1. Chute 5 is inclined downwardly and laterally from the main chute 1 and thus it will be seen that when a body of coal is flowing along the main chute 1, a portion thereof will be divided from the rest by the curved deflecting portion 8 of the wall 7 and thus be directed into the upper delivery chute 5. The intermediate tongue 3 is secured on and forms a 80 part of the bottom of an intermediate side delivery chute 9 similar to the chute 5 and extending thereunder, this chute 9 having upstanding side walls 10 and 11, the wall 11 merging into an arcuate deflecting end 12 corresponding with the deflecting wall 8 85 and extending up to the inner end of the tongue 3 supporting it. Thus it will be seen that that portion of the body of coal passing between the wall 8 and the remote side of the chute 1 will be divided, a portion thereof being deflected onto the chute 9 by the deflecting wall 12. The lowermost tongue 3 is secured to and forms a part of the bottom of the lower side delivery chute 95 13 which extends under the chutes 5 and 9 and has upstanding side walls 14 and 15. The side wall 15 merges into an arcuate deflecting wall 16 which extends from one side wall 2 of the chute 1. Thus it will be

seen that that portion of the coal which 100 105 110

does not enter the chute 9 will flow downwardly and be deflected into chute 13 by the wall 16.

From the foregoing description it will be apparent that as a body of coal is moving downwardly along the chute 1 it will be divided into separate streams, these streams flowing into the superposed side delivery chutes 5, 9 and 13 and as the discharge ends of these chutes are secured to or rest upon the superposed shelves or tiers of a separator, it will be obvious that coal can pass freely from the main chute 1 to the separator without falling at any point and, consequently, breakage will be practically eliminated.

Although a specific construction of chute has been shown and described, it is to be understood that this construction may be varied at will provided side delivery chutes are mounted in the desired relation to the main chute whereby as a body of coal moves downwardly along the main chute, it will be divided into separate streams, which streams will be deflected laterally in superposed relation. Although only three side delivery chutes have been shown combined with the

main chute, it is to be understood that this number may be increased or diminished as desired.

30

What is claimed is:—

A feed chute for coal separators, including a main chute having tongues extending from the discharge end thereof, said tongues being disposed in stepped relation and each having a curved side, side delivery chutes having their bottoms secured to the respective tongues, upstanding walls upon the respective side delivery chutes, one of said walls constituting a deflector and being extended partly across the main chute and along the curved edge of the tongue to which the side delivery chute is secured, all of the side delivery chutes being disposed in superposed relation and having their bottoms constituting continuations of the bottom of the main chute.
